J. W. PITT

PRINTER'S PLATE HOOK

Filed Oct. 4, 1924

INVENTOR:
JOHN W. PITTS
BY
CHARLES G. GILLETT
ATTORNEY.

UNITED STATES PATENT OFFICE.

JOHN W. PITTS, OF BATH, NEW YORK.

PRINTER'S PLATE HOOK.

Application filed October 4, 1924. Serial No. 741,537.

To all whom it may concern:

Be it known that I, JOHN W. PITTS, a citizen of the United States, and a resident of Bath, in the county of Steuben and State 5 of New York, have invented certain new and useful Improvements in Printers' Plate Hooks, of which the following is a specification.

The object of the invention is provide a 10 highly efficient plate-hook for the use of printers in securing stereotype, electrotype and other printing plates on the bed or cylinder of a printing press, and a further purpose of the invention is to provide a 15 plate-hook which may be quickly and firmly applied to position and conveniently detached, when desired, from the plate and bed. One of the objects of the invention is also to provide a plate-hook which is readily 20 adjustable to the irregularities frequently found on the edges of printing plates, and a further object of the invention is to provide a plate-hook whose parts may remain in assembled relation, whether on a printing 25 press or held in stock, it being unnecessary with my present invention that the parts of the plate-hook need ever be entirely disassembled after said parts have been once brought together.

30 The invention resides in the novel features, structure and combinations herein-after described, and particularly pointed out in the claims, and which invention I desire to broadly protect.

35 Referring to the accompanying drawings: Fig. 1 is a top view of a portion of the bed of a press having thereon a printing plate held by hooks constructed in accordance with and embodying my invention, six 40 of the hooks being shown;

Fig. 2 is a vertical section, on a larger scale, through a portion of the same, the section being on the dotted line 2-2 of Fig. 1;

Fig. 3 is a transverse section through a 45 portion of the bed of the press and illustrates the plate-hook of my invention in the initial position given to its parts on introducing the same to the groove of the bed of the press;

Fig. 4 is a corresponding view taken on the dotted line 4-4 of Fig. 1, illustrating the plate-hook of my invention in its 50 final position when secured in the groove of the bed and in engagement with the printing plate;

Fig. 5 is a top view of the body portion of the plate-hook, with the clamp member shown in horizontal section, and

Fig. 6 is a vertical section through portions of the bed of the press and the plate 60 thereon, and through one of the hooks, the section being on the dotted line 6-6 of Fig. 1.

In the drawings, 20 designates a section of a well-known form of type-bed or block 65 or the surface of a cylinder, upon which an electrotype or other printing plate 21 is shown as secured by the plate-hooks of my invention, said bed, block or cylinder being formed with parallel diagonally disposed 70 grooves 22, which in the construction shown, are of dove-tail formation or have inwardly diverging overhanging side walls. The plate 21 is also of customary form and has downwardly and outwardly beveled edges, as 75 usual.

My invention resides in the novel hooks or clamps adapted to the grooves of the bed 20 and affording means for very firmly and effectually securing the plate 21 in proper 80 position on said bed.

Each of the hooks, referring to Figs. 1 to 6 inclusive, is composed of two main members or features, one of these features being a body-portion 23 having a longitudinally 85 projecting extension 24 provided on its forward end with a head 50, and the other being a block 25 having thereon a clamping member 26 carrying a screw 27.

The body portion 23 is also provided with 90 a screw 28, and said body portion is oblong in transverse section and has two opposite flat sides and two opposite segmental sides, as shown in Figs. 3 and 4, with the lesser transverse dimension adapted for entrance 95 through the mouth of the dove-tail groove 22, as shown in Fig. 3, and its greater transverse dimension greater than the width of said mouth, as shown in Fig. 4.

The screw 28 extends transversely through 100 the body 23 across its lesser diameter or between the opposite flat sides of said body, as shown in Fig. 2, the body 23 being formed with a threaded hole through it to receive said screw 28, which has a polygonal bore 105 to receive the end of an operating key and a flat inner end to engage the flat bottom of the groove 22, as shown in Fig. 2.

The extension or stem 24 is, generally speaking, of cylindrical outline at its sides 110

and lower part and it is loosely fitted within the cylindrical bore 35 of the block 25, and near its outer end said extension or stem 24 is formed with a shoulder 36, between which and the body 23 the extension or stem 24 has a flat downwardly and outwardly inclined smooth surface 37, which is adapted to receive the flat lower end of the screw 27, as shown in Fig. 2, whose longitudinal axis stands at a right angle to said surface 37, and which screw is within a threaded opening or hole 38 in the block 25. The screw 27 has a polygonal bore to receive an operating key of common type. The extension 24 on its forward or outer end, is provided with a head 50, which has substantially flat upper and lower sides and rounded vertical sides and follows the general shape and proportions of the body 23. The head 50, when the body 23 is turned to present its flat sides to the mouth of the groove 22, as shown in Fig. 3, takes a corresponding position and passes downwardly through the mouth of the groove 22, and then when the body 23 is restored to its normal transverse position shown in Fig. 4, the head 50 takes a corresponding position across the groove 22, as shown by the dotted lines in Fig. 1. The forward end of the stem 24 is of reduced diameter, as at 51 (Fig. 2), and at the inner end of this reduced portion of the stem there is formed, by reason of the reduction, a shoulder 52. The head 50 has a central bore and tightly fits upon the reduced end 51 of the stem 24 and abuts against the shoulder 52, as shown in Fig. 2, and said head 50 is finally secured in rigid relation to the stem by means of a vertical pin 53 which passes through the head and the reduced end 51 of the stem 24. I regard the presence of the head 50 on the forward end of the stem 24 as of special importance. The vertical sides of the head 50, when the screw 27 is tightened against the base of the groove 22, become wedged upwardly, with the body 23, against the opposing downwardly diverging walls of the groove 22, and at this time the head 50 serves the important purpose of preventing the forward end of the stem 24 from tilting upwardly, the presence of the body 23 and head 50 serving to maintain the stem 24 in precise parallelism with the groove 22, said head having the same sustaining action for the forward end of said stem as the body 23 has for the other end of said stem. I have found in practice that in the absence of the head 50 there is a tendency for the forward end of the stem 24 to tilt upwardly when the screw 27 is screwed downwardly, and to overcome this particular action is one purpose of the head 50. The head 50 is applied to the stem 24 after said stem has

been passed into and in part through the bore 35 in the block 25.

The block 25 may be of ordinary rectangular outline adapted to the grooves of the bed 20, and the clamping member 26 thereon is preferably formed integrally therewith. The block 25 contains the longitudinal or cylindrical bore 35 adapted to detachably receive the extension or stem 24, which is rigid with the body 23, and preferably said extension or stem and said body are in one piece. 75

The polygonal bores in the screws 27, 28 preferably have corresponding transverse dimensions so that one operating key may 80 serve for tightening and loosening both screws.

The stem or spindle 24 is cylindrical in its side and lower portions so that the block 25 may have angular adjustment thereon to 85 permit the clamping member 26 to engage the beveled edges of the plate 21 regardless of such irregularities as may be present on said edges, and the outer edge of the member 26 which engages the plate 21 is downwardly and inwardly beveled or undercut, as shown in Fig. 2, so as to lap upon and closely engage the edge of said plate. 90

In assembling the several features of my plate-hook, the block 25 is slid upon the extension or stem 24 and the head 50 is then secured to said stem and the screw 27 is then applied to position. The screw 28 may then also be applied to position, the screw 28 being substantially concealed within the threaded hole therefor in the body 23, and the screw 27 being worked downwardly until the point of the screw is below the horizontal plane of the upper edge of the shoulder 36 and over the inclined 105 surface 37 of the stem 24. When the parts 23, 25 are thus brought together, they may be handled as a unit, since the screw 27 and shoulder 36 constitute stops which prevent the accidental separation of said parts. 110

In applying the plate-hook upon the bed 20, I first loosen the screw 27, without entirely detaching it, and then turn the body 23 so that its flat sides and the flat sides of the head 50 stand vertical, or in the position indicated in Fig. 3. In this position of the body 23 and head 50 I may drop said body downwardly within the groove 22 of the bed 20, the block 25 entering said groove at the same time, while the clamping jaw 26 remains on the top of the bed and extends across the groove 22. After the body 23, stem 24 and head 50 have been entered downwardly into the groove 22, I then slide the plate-hook as a whole toward the plate 21 and until the outer edge of the clamping jaw 26 passes into approximately close engagement with the beveled edge of said plate. Thereafter I impart a partial turn to the body 23, so that the flat sides of said body 120

and of the head 50 may be carried to a horizontal position parallel with the surface of the bed 20 or to the relation indicated in Fig. 4, this partial rotation of said body 23 5 also serving to position the segmental side portions of said body and of said head 50 in close relation to the undercut side surfaces of the groove 22. The body 23 and head 50 are at this time in position to be 10 bound to the bed 20, and in order to firmly secure the body 23 and head 50 in fixed position within the groove 22, I, with the use of a key, work the screw 28 downwardly against the bottom of the groove 22 and thereby wedge upwardly the body 23 and head 50 against the inclined overhanging sides of said groove, said body and head 15 thus becoming assuredly secured in fixed position. The screw 28 is thus a tightening 20 and wedging screw for the body 23. After the body 23 has been firmly secured in position, I, with the use of the key used for tightening the screw 28, work the screw 27 downwardly against the inclined or wedge 25 surface 37 of the spindle, extension or stem 24, and this will have the effect of causing the block 25 to move outwardly or in a direction toward the outer end of said spindle or stem 24 until it becomes arrested by a 30 very firm clamping engagement of the inclined edge of the clamping member 26 with the beveled edge of the plate 21, whereupon the movement of said block 25 will cease, but the clamping member 26 will, by the 35 action of the screw 27 and wedge-surface 37, remain firmly bound against the plate 21, while the body 23 and stem 24 remain securely held against longitudinal movement due to the screw 28 and the wedging 40 of the segmental sides of said body and of the head 50 against the inclined walls of the groove 22.

When it is desired to release the plate-hook from the plate 21 and possibly from the bed 20, I loosen the screws 27, 28 and give the body 23 a half-turn so as to bring its flat sides and the flat sides of the head 50 into vertical position, and thereupon the plate-hook as a whole may be slid along the groove 22 and, if desired, elevated therefrom, the plate 21 then being fully released.

Frequently the edges of the plates 21 are or become irregular, and my invention adapts the clamping member 26 to engage 55 the edge of the plate regardless of its peculiarities of formation, since the block 25 may turn or swivel angularly to a sufficient extent on the extension or stem 24, whenever required, to adapt the edge of the 60 clamping member to the edge of the plate, this angular adjustment of the jaw or plate 26 being automatic during the tightening of the screw 27 against the extension or stem 24 and being caused by such irregularity 65 as the edge of the plate may possess

and which may force the block 25 and jaw 26 to adapt themselves to the condition of the plate. The angular adjustment just described of the jaw or hook 26 is permitted from the fact that the block 25 70 and body 23 are swiveled together by the spindle or stem 24 which is on one of said parts and freely enters a socket or hole in the other part.

I have found that there is a distinct advantage in providing the screw 28 with a flat inner end to engage the flat bottom of the groove 22, since with the use of the flat ended screw I secure a regularity of position and movement in the body 23 which assures the correct and equal movement and wedging of the segmental sides of said body against the opposite side walls of the groove 22, the flat end of the screw and the presence of the head 50 serving to prevent any 75 tilting action of the body 23 tending to prevent the regular upward movement of both segmental sides of said body uniformly. I have also found that there is a distinct advantage in providing the screw 27 with a 80 flat inner end to engage the flat surface 37 of the stem 24. I therefore preferably use flat ended screws 27, 28, and I have also found that the use of screws having polygonal bores to receive a key is advantageous 85 from points of efficiency and durability over the employment of screws having the usual slotted ends to be engaged by a screwdriver.

I preferably distinguish the plate-hooks 100 intended for the transverse side edges of the plate 21 from those intended for the end edges thereof, by beveling the ends of the clamping members 26 intended for said side edges, as at 70, and giving the ends of the 105 clamping members intended for said end edges a straight or right angle shape, as at 71. The plate hooks whose clamping members have the beveled edges 70 and straight edges 71, respectively, I designate as rights 110 and lefts.

The two plate hooks shown at the lower left hand corner of Fig. 1 are identical with the other plate hooks illustrated in the drawings except that in respect to said two plate hooks I form the clamping members 72 thereof of triangular outline and correspondingly bevel the forward diverging edges of said members so that either of said edges may be used to engage the edge of a 120 printing plate 21. When the plate hooks have the triangular clamping members 72, all of the plate hooks in use may be exactly alike, since with this construction the clamping members may be engaged with either the transverse side edges of the printing plate or the end edges thereof, as will be understood on reference to Fig. 1.

I have hereinbefore described in specific detail the most efficient forms of plate-hooks 130

known to me embodying my invention, but I do not limit my invention to all of the details of form and structure shown and described, since I am aware that some thereof are capable of modification without departure from the spirit of my invention and within the scope of the appended claims.

What I claim as my invention and desire to secure by Letters Patent, is:

13. 1. A printer's plate-hook adapted to the dove-tail grooves in the beds and the like of presses, comprising an elongated integral body-member having a stem projecting longitudinally from one end thereof and formed 15 with a downwardly and forwardly inclined upper surface, said body-member being oblong in transverse section with the lesser transverse dimension adapted for direct downward entrance through the mouth of the dove-tail groove and the greater transverse dimension greater than the width of said mouth, said body being in transverse sectional contour adapted for turning about a longitudinal axis when entered within the 20 groove and having a tightening screw set through the same transversely of its greater transverse dimension for impingement on the flat bottom of the groove for tightening the body in the groove by crowding the body 25 up against the overhanging sides of the groove; and a block receiving and slideable longitudinally on said stem and carrying a plate-clamping jaw and also a screw adapted to be engaged with said inclined surface for 30 moving said block and jaw.
16. 2. A printer's plate-hook as claimed in claim 1, in which said elongated body-member has convex opposite sides extending below the overhanging walls of the dove-tail groove and flat upper and lower surfaces. 40
17. 3. A printer's plate-hook as claimed in claim 1, in which both the said screws have polygonal bores of corresponding transverse dimensions so that one operating key may 45 serve for tightening and loosening both screws.
18. 4. A printer's plate-hook as claimed in claim 1, in which the plate clamping jaw is of triangular formation and has two diverging edges either of which may engage the plate.
19. 5. A printer's plate-hook adapted to the grooves in the beds and the like of presses, comprising a body member having a stem 55 projecting forwardly from one end thereof having on its forward end a head, said body member and head adapted to be turned angularly and being of a contour permitting them when turned in one position to be entered within the groove and when thereafter turned to another position to be caught within the groove, said body-member having a screw to engage the bottom of the groove and wedge said member and said head upwardly against the overhanging side walls 60 of the groove, a second member slideably mounted on said stem and having a plate clamping jaw, and means for giving the jaw-carrying member its plate clamping movement, said stem at its forward end being of reduced diameter and having a shoul-

of the groove, a second member slideably mounted on said stem and having a plate clamping jaw, and means for giving the jaw-carrying member its plate clamping movement.

6. A printer's plate-hook adapted to the grooves in the beds and the like of presses, comprising a body member having a stem projecting forwardly from one end thereof having on its forward end a head, said body member and head adapted to be turned angularly and being of a contour permitting them when turned in one position to be entered within the groove and when thereafter turned to another position to be caught within the groove, said body-member having a screw to engage the bottom of the groove and wedge said member and said head upwardly against the overhanging side walls of the groove, said stem having a downwardly and forwardly inclined upper surface, and a second member swiveled and slideable on said stem and having a plate clamping jaw and a screw to engage said inclined surface of the stem and give said jaw carrying member its plate clamping movement.

7. A printer's plate hook adapted to the grooves in the beds and the like of presses, comprising a body-member having a stem projecting forwardly therefrom provided on its forward end with a head, said body-member and head having flat upper and lower surfaces and rounded sides and adapted on being turned angularly in one position to be entered within the groove and when thereafter turned to another position to be caught within the groove, said body-member having a screw to engage the bottom of the groove and wedge said member and said head upwardly against the overhanging side walls of the groove, a second member slideably mounted on said stem and having a plate clamping jaw, and means for giving the jaw carrying member its plate clamping movement.

8. A printer's plate-hook adapted to the grooves in the beds and the like of presses, comprising a body-member having a stem projecting forwardly from one end thereof having on its forward end a head, said body member and head adapted to be turned angularly and being of a contour permitting them when turned in one position to be entered within the groove and when thereafter turned to another position to be caught within the groove, said body-member having a screw to engage the bottom of the groove and wedge said member and said head upwardly against the overhanging side walls of the groove, a second member slideably mounted on said stem and having a plate clamping jaw, and means for giving the jaw-carrying member its plate clamping movement, said stem at its forward end being of reduced diameter and having a shoul-

der at the back end of such reduced portion, and said head fitting upon said reduced portion and against said shoulder and being secured by a pin extending transversely 5 through said head and such portion.

9. A printer's plate-hook adapted to the grooves in the beds and the like of presses, comprising an integral body-member having a stem projecting forwardly from one end 10 thereof, said body member being of a transverse contour permitting it when turned on edge and at a right-angle to the bed to be entered within the groove and when thereafter given a reverse one-half turn to be 15 caught within the groove, said body member having a screw to engage the bottom of the groove and wedge said member upwardly against the overhanging side walls of the groove, a second member swiveled and slide- 20 able on said stem and having a plate clamping jaw, and means for giving the jaw-carrying member its plate clamping movement.

10. A printer's plate-hook adapted to the grooves in the beds and the like of presses, 25 comprising an integral body-member having a stem projecting forwardly from one end thereof, said body-member being of rectangular horizontal outline and having flat upper and lower surfaces and rounded sides 30 and adapted when turned in one position to be entered within the groove and when thereafter turned to another position to be caught within the groove, said body-member having a screw to engage the 35 bottom of the groove and wedge said member upwardly against the overhanging side

walls of the groove, a second member swiveled and slideable on said stem and having a plate clamping jaw, and means for giving the jaw-carrying member its plate clamping 40 movement.

11. A printer's plate hook adapted to the grooves in the beds and the like of presses, comprising an integral body-member having a stem projecting forwardly from one end 45 thereof, said body-member being of a transverse contour permitting it when turned in one position to be entered within the groove and when thereafter turned to another position to be caught within the groove, said body-member having a hollow screw to engage the bottom of the groove and wedge said member upwardly against the overhanging side walls of the groove, said stem having a downwardly and forwardly inclined upper surface, and a second member swiveled and slideable on said stem and having a plate clamping jaw and a hollow screw 50 to engage said inclined surface of the stem and give said jaw carrying member its plate 55 clamping movement, said hollow screws having corresponding polygonal bores for co-operation with a single operating key.

12. A printer's plate-hook as claimed in 60 claim 5, in which the plate clamping jaw is 65 of triangular formation and has two diverging edges either of which may engage the plate.

Signed at Bath, in the county of Steuben and State of New York, this first day of 70 October, A. D. 1924.

JOHN W. PITTS.
